GARMENT HANGER

Stuart Lawrence Fuller, Detroit, Mich.

Application March 20, 1935, Serial No. 11,940

3 Claims. (Cl. 223—96)

This invention relates to a garment hanger and more particularly to a device of this character particularly adapted for suspending trousers.

An object of the invention is to provide a device for the purpose which is simple in construction and cheap to manufacture, and wherein the construction is such as to particularly adapt it to be made entirely of metal.

A further object is to so construct the clamping and suspending members of the device as to greatly facilitate the assembly, and further, to so attach the clamping members to the suspending members as to permit the clamping members to maintain parallel relation of their adjacent 15 surfaces which contact the garment, and thus prevent creasing of the garment, as would result if these members clamped the garment with the members in angular relation.

A further object is to provide simple means for 20 yieldingly forcing the clamping members into clamping engagement with the garment, by a simple movement of a hook forming a part of the suspending means, said hook serving to spread apart cam portions of said suspending and connecting means for said clamping members. It is 25 a further object to so construct the suspending and operating means for the clamping members, that said means may be conveniently formed from spring wire, and the invention also consists in 30 certain other new and useful features of the construction, arrangement and combination of parts, all as hereinafter more fully set forth, reference being had to the accompanying drawing, wherein:

Fig. 1 is a side elevation of a device illustrative 35 of an embodiment of the invention and showing portions broken away and in section to more clearly disclose the construction;

Fig. 2 is a section substantially upon the line 40 2—2 of Fig. 1;

Fig. 3 is an end elevation of the device shown in 45 Fig. 1;

Fig. 4 is a vertical section through the device substantially upon the line 4—4 of Fig. 1, and

Fig. 5 is an end elevation of the device showing the same in open position to receive the garment 50 between the clamping members.

In order to simplify the construction and its manufacture and assembly, the two garment 55 clamping members 1 are preferably stamped from sheet metal with a turned out edge flange 2 extending along the entire edges and ends of the web portion 3 of each member. Further each member is offset laterally as at 4 intermediate its ends to provide for the thickened portion

of the garment, such as the side seams of the legs of trousers, and in the upper side of the flange 2 adjacent this offset portion of each clamping member, are elongated slots or openings 5, and on the web 3 of each clamping member adjacent and below the openings 5, are struck out ears 6 each provided with a hole to receive a laterally bent end portion 7 of the legs 8 of two bails 9 and 10, each bail being formed of wire with a loop or eye 11 intermediate or at the juncture of the legs 8 of the bails with the upper curved connecting portions 12 and 13 of the bails 9 and 10, which curved portions connect the upper ends of the legs 8, and these bails are pivotally connected by means of a transverse pivot 14, the ends of which extend through the eyes 11 of the two bails and are provided with washers 15 thereon engaging the outer sides of the eyes and the ends of the rod 14 are headed or riveted down to hold the washers in place, and thus 20 the two bails are pivotally connected.

The legs 8 of the two bails 9 and 10 are offset laterally adjacent the eyes 11 to space the clamping members 1 apart and the looped or cam portions 12 and 13 of the bails are so proportioned 25 that when the clamping members are spread apart, as shown in Fig. 5, the loop or curved portion 12 of one bail will pass partially through the curved or cam portion 13 of the other bail, and a wire hook 16 is pivoted at the lower end of 30 its straight shank portion 17, as at 18, to the pivot rod 14 intermediate the ends of the rod to swing upon its pivot in a direction longitudinally of said rod. The hook is thus free to swing 35 between the overlapping cam portions 12 and 13 of the two bails, and when the hook is turned to a substantially horizontal position, the loops or cam portions of the two bails are free to pass, the loop 12 a limited distance through the loop 13, and thus allow for the swinging movement 40 and spreading apart of the clamping members 1, but when this hook 16 is turned to a vertical position between the cam portions of the bails, these overlapping cam portions will be spread apart 45 by the shank portion 17 of the hook coming therebetween, and thus the two clamping members 1 will be swung toward each other upon their pivotal connection, or pivot rod 14, to clamp the garment therebetween.

As the two bails are formed of spring wire, the 50 connecting or cam portions 9 and 10 will yield sufficiently to permit the hook to be turned to a vertical position between these loops regardless of the thickness of the portion of the garment clamped between the members 1, and the legs 8 55

of the bails will also yield under such conditions, applying a yielding clamping force to the two clamping members. The arrangement of the overlapping curved portions 12 and 13 of the 5 two bails with the suspending hook interposed therebetween, provides a simple clamping action for drawing the members 1 toward each other with a yielding force and when the garment is suspended by means of the hook 16, the hook 10 will be held thereby in proper position between the two bails to firmly hold the garment clamped. Further with this construction, the assembly of the bails and clamping members 1 is greatly facilitated because the laterally bent ends 7 of the 15 legs 8 of the two bails may be readily entered through the slots 5 in the flanges 2 and these ends then engaged within the openings in the ears 6 to pivotally attach the members 1 and bails.

20 Due to the width of these slots 5 through which the legs of the bails extend, and the pivotal attachment of the lower ends of the legs to the webs 3 of said clamping members, each clamping member is free to rock laterally about the bent 25 ends 7 of the bails and thus when a garment is clamped between the clamping members by the swinging of the legs of the bails toward each other, the members will rock upon such pivotal connections, as they come in contact with the 30 garment, and maintain the parallel relation of their inner faces to evenly engage the garment, instead of being held in a vertical inclined position by their connection with the bails which would otherwise position the upper edges of the 35 members closer together than their lower edges and thus clamp the garment unevenly, causing them to mark or crease the garment by such uneven pressure thereon.

Further, this manner of connecting the bails 40 to the clamping members permits the complete assembly of the bails before their attachment to the clamps, as the ends of the bails may be readily inserted through the openings 5 after the bails have been pivotally connected by the securing of 45 the pivot rod within the eye 11 formed on the bails. With this arrangement of the hook 16 the operation of clamping the garment between the clamping members, is greatly facilitated, as these members may be quickly applied to the 50 garment while spread apart, and then by swinging the hook between the overlapping, curved portions of the bails, said members are forced into clamping position against opposite sides of the interposed garment, and this locked condition is maintained by the hanging of the garment 55 up by means of the hook.

An all metal garment hanger of simple construction is thus provided and the operation thereof is facilitated.

60 Obviously the device may be modified as to details of construction and arrangement of parts without departing from the spirit of the invention, and I do not, therefore, limit myself to the particular construction, arrangement and combination shown.

What I claim is:—

1. A garment hanger comprising a pair of opposed clamping members, a bail secured at one end to each of said clamping members and extending laterally therefrom with said bails pivotally connected together intermediate their

ends, each bail being formed with a curved outer closed end portion, one of said end portions of one bail being of lesser length than the other to swing through the closed end portion of the other bail into crossed relation thereto, a member forming the pivotal connection between said bails, a suspension member formed of wire and pivotally attached at one end to said pivot member to swing longitudinally of said closed ends of said bails with its shank portion between said closed outer curved ends of said bails and spread the same apart and move said clamping members into clamping position, said suspension member being held in midposition of its swinging movement by the engagement of said bails therewith. 15

2. A garment hanger comprising a pair of opposed clamping members, a bail for each clamping member with the ends of each bail connected to a clamping member with the bail extending laterally therefrom, each bail having a closed curved outer end and formed with eyes intermediate its ends, a pivot rod extending through said eyes across said bails to pivotally connect said bails, said bails extending from said eyes outwardly in crossed relation when said clamping members are in separated position, and a suspension member pivotally attached at one end to said rod intermediate the ends thereof to swing thereon longitudinally of said clamping members between said bails to a position substantially parallel with said rod and permit said clamping members to spread apart and to swing to midposition between said bails to spread the same apart and move said clamping members into clamping position. 30

3. A garment hanger comprising a pair of clamping members each formed of sheet metal with a projecting edge flange and openings in said flange, a bail for each clamping member, each bail having leg portions to extend loosely through said openings in said flange, said legs having laterally turned end portions to pivotally attach said legs to said clamping members and permit turning movement of said clamping members upon said lower ends of said legs in a direction transversely of each clamping member, each bail being formed with an eye intermediate its ends and with an outer curved end portion connecting the legs of each bail, a pivot rod extending through said eyes of said bails to pivotally connect said bails and said clamping members, and a suspension member formed of wire and having a shank portion pivotally attached at one end to said rod intermediate the ends thereof to swing in a direction longitudinally of said clamping members between said bails, the closed outer end portions of said bails being arranged to swing, one through the other into crossed relation when said suspension member is swung with its shank substantially parallel with said rod and to be spread apart by the swinging of said suspension member to midposition with its shank engaged between said crossed portions of said bails, said suspension member having a hook portion at its free end for suspending the device from a support and for holding said suspension member in mid position of its swinging movement between said bails and hold said clamping members in clamping position. 60
